CLAIM

The ornamental design for cooking apparatus, as shown and described.

DESCRIPTION

FIG. 1 is a perspective view of a cooking apparatus showing my new design, with the top cover closed and the side shelves in a lowered position;

FIG. 2 is a front elevational view thereof;

FIG. 3 is a left side elevational view thereof;

FIG. 4 is a right side elevational view thereof;

FIG. 5 is a top plan view thereof;

FIG. 6 is a rear elevational view thereof;

FIG. 7 is a perspective view thereof, with the top cover open and the side shelves in a raised position;

FIG. 8 is a front elevational view of FIG. 7;

FIG. 9 is a left side elevational view of FIG. 7;

FIG. 10 is a right side elevational view of FIG. 7;

FIG. 11 is a top plan view of FIG. 7; and,

FIG. 12 is a rear elevational view of FIG. 7.
